J. C. TAYLOR,
CAR COUPLING,
APPLICATION FILED JAN. 15, 1917.

1,318,241.

Patented Oct. 7, 1919.

UNITED STATES PATENT OFFICE.

JOHN C. TAYLOR, OF FINDLAY, OHIO.

CAR-COUPING.

1,318,241.

Specification of Letters Patent.

Patented Oct. 7, 1919.

Application filed January 15, 1917. Serial No. 142,505.

To all whom it may concern:

Be it known that I, JOHN C. TAYLOR, a citizen of the United States, residing at Findlay, in the county of Hancock and State 5 of Ohio, have invented certain new and useful Improvements in Car-Couplings, of which the following is a specification, reference being had therein to the accompanying drawing.

10 My invention relates to improvements in car couplings, and more particularly to an improved locking block which is adapted to be used with a coupling of the Janney type, such as is shown in my U. S. Patent No. 15 1,098,135, dated May 26th, 1914.

15 The object of the present improvement is to devise an improved means for holding the locking block in such a position that the knuckle may enter the draw-head of the 20 coupling and at the same time trip the holding means and permit the locking block to move into place for locking the knuckle in the draw-head.

25 Another object of the present improvement is to so construct the locking block and its holding means, that upon moving the locking block to release the knuckle the said holding means will automatically retain the locking block in open position so 30 that the knuckle may enter the draw-head when it is desired to again lock the coupling.

35 Other objects and advantages of the present improvement will be set forth in the following description and drawings, in which—

Figure 1 is a top plan view of a coupling embodying my invention, showing the draw-head partly broken away to show the knuckle and the locking block.

40 Fig. 2 is a perspective view showing the draw-head partly broken away, the knuckle in open position and the locking block in position to receive the knuckle for locking the coupling.

45 Fig. 3 is an enlarged fragmentary vertical sectional view of the draw-head and a side elevation of the locking block showing it held open to receive the knuckle.

Fig. 4 is a front view of Fig. 3.

50 Fig. 5 is a view similar to Fig. 3, showing the locking block in its locked position for holding the knuckle in the draw-head.

55 Referring now to the drawings in detail, in which like reference numerals designate similar parts throughout the several figures, 1 represents the draw-head which is of the

ordinary Janney type exterior and needs no further description. The draw-head is provided at its lower end with a recess 2 to receive a locking block 3. This recess 2, as 60 shown, is arranged directly in the center of the draw-head and the locking block 3 is adapted to slide thereinto to lock the knuckle in its inward position, as will be hereinafter more fully described. The draw-head at one 65 side is provided at its upper and lower edges with outwardly extending parallel horns, one of which 4 is shown. The knuckle 5, which is of the character shown in my Patent No. 1,098,135 is pivotally mounted 70 in a manner similar to the said patent between the said parallel horns. The knuckle is provided with a portion 6, which is adapted to extend across the draw-head and forms the coupling which interlocks with a 75 similar coupling carried by the other car. The said knuckle 5 is also provided with a member 7, which when the knuckle is in its open position, passes inwardly into the hollow draw-head and the locking block 3 80 moves downwardly into the slot 2 beyond the said member 7, which is engaged by the said locking block thereby preventing the knuckle from swinging outwardly.

85 The locking block 3 comprises a pear-shaped body portion having an eye 8 in its upper end to which a suitable rod or lever 8' is connected for raising and lowering the said block to lock and release the knuckle 5. A holding means, comprising a plate 9, having a hole 10 in its upper end, is pivotally attached to one side of the locking block by 90 means of a stub-shaft 11, carried integral with the locking block. The said plate 9 has a portion 12 extending at right angles to the 95 balance of the plate which portion is provided with a tongue 13 that is adapted to oscillate within a slot 2^a in the drawhead and to coöperate with a notch 15 cut in the front wall of the draw-head, which also 100 forms the front end of the slot 2^a.

105 In operation, when the knuckle is open, as is shown in Fig. 2, the locking block 3 and its holding means will occupy the position shown in Fig. 3. When the knuckle 5 is 110 swung inwardly to lock the coupling, the portion 7 thereof, which is provided with an engaging boss 14, will strike the end 12 of the plate 9 forcing the tongue 13 out of the notch 15 in the end of the draw-head, thus permitting the portion 7 to enter the draw-head, and the locking block 3 to slide

down in the position shown in Fig. 5, and lock the knuckle. In opening the coupling the reverse operation takes place, the locking block being raised, the knuckle is freed and at the same time the tongue 13 of the plate 9 due to the shape of the said plate, is slid into the notch 15 in the draw-head, thus holding the locking block 3 and holding means 9 in position to be engaged by the boss 14 on the portion 7 of the knuckle for locking the coupling.

Having thus described my invention what I claim and desire to secure by Letters Patent is:—

- 15 1. A car coupling comprising a draw-head, an oscillating locking block, the said block oscillatable from a position at substantially right angles to the draw-head into a position substantially parallel thereto, and
- 20 2. a holding member pivoted to the block, said member moved vertically by the oscillation of the said block whereby it is substantially parallel with the block when the said block is at right angles to the draw-head and is at substantially right angles to the block when the block is parallel with the draw-head.
- 25 2. A car coupling comprising a draw-head, an oscillatable locking block, and a holding member pivoted thereto and moved vertically by the oscillation of the said block.
- 30 3. A car coupling comprising a draw-

head having a recess therein, an oscillatable locking block at one side of the recess, and a holding member pivoted to the side of the locking block and vertically movable within the recess by the oscillation of the said block.

4. A car coupling comprising a draw-head having two slots side by side, a locking block oscillatable in one slot, and a holding member pivoted to the side of the said block and vertically movable in the other slot by the oscillation of the locking block.

5. A car coupling comprising a draw-head, a locking block reciprocatable in a horizontal plane, and a holding member pivoted thereto and movable in a vertical plane by the reciprocation of the locking block.

6. A car coupling comprising a draw head having a recess in the upper face thereof, and a notch formed in one wall of the recess adjacent its top edge, a reciprocable locking block and a holding member pivoted to the locking block and vertically movable within the said recess, said member having a cut away portion on one edge to mesh with the said notch.

In testimony whereof I hereunto affix my signature in the presence of two witnesses.

JOHN C. TAYLOR.
